TREAT T. PROSSER, OF CHICAGO, ILLINOIS.

Letters Patent No. 91,963, dated June 29, 1869.

IMPROVED MACHINE FOR FORMING THREADS ON SCREWS.

The Schedule referred to in these Letters Patent and making part of the same.

To all whom it may concern:

Be it known that I, TREAT T. PROSSER, of Chicago, in the county of Cook, and State of Illinois, have invented a new and useful Improvement in Screw-Forming Machines; and I do hereby declare that the following is a full, clear, and exact description of the same, reference being had to the annexed drawings of a machine including my improvements.

Figure 1 is a plan view of said with some of the parts broken away, to show the interior of those parts.

Figure 2 is a bottom view of the same, showing the arrangement of the gearing for driving the machine.

Figure 3 is an end elevation.

Figure 4 is a side elevation of the guide for the rod upon which the screw is to be formed, showing also an end view of the disk or cap, with grooves and projections for forming the threads.

Figure 5 is a transverse vertical section of the guide on line *x* *x* of fig. 4.

Figure 6 is a longitudinal central section on line *y* *y* of fig. 1.

Figure 7 is a plan view, partly in section.

Corresponding letters in all the figures refer to corresponding parts.

My invention relates to machines for forming screw-threads upon bolts, or metallic bars of any kind adapted to the purpose; and

My improvement consists in forming such threads by compression between plates having concentric projections upon their faces, set at an angle to one another, and revolving upon axes in different planes, and in such modifications of construction and arrangement as will be hereinafter specifically indicated.

A, in the drawings, represents the frame of the machine, which may be constructed as shown, or in any other suitable manner, it being provided with suitable boxes for the reception of the shafts of the driving-gearing, and with proper receptacles for the screw-forming disks or cups, and for the gears, and it may also be provided with a reservoir for water, as shown in fig. 6, so that the screw-forming disks may enter such water as they rotate, and thus be kept cool, and at the same time carry to and deliver upon the surface of the rod or bolt, an amount of water sufficient to cause the scale to be removed from such bolt.

B B' represent the shafts, to which are to be secured the larger gear-wheels *C C'*, and the screw-forming disks or caps *F F'*.

These shafts are fitted to and revolve in the boxes *b* and *b'*, formed in or secured to the frame *A*, as clearly shown in figs. 1 and 6 of the drawings; the object of placing these shafts at an angle to each other, as shown in fig. 1, being to throw those portions of the screw-forming disks or cups which, for the time being, are opposite the point where they come in contact with and operate upon the bolt, at such a distance

from each other as to permit the full diameter of such bolt to pass between their outer surfaces without coming in contact therewith, while those points which approach nearer to each other, may be made to penetrate the bolt to the extent required to form the thread upon such bolt.

The arrangement of these shafts, and the screw-forming disks or cups which are secured thereto, shown in fig. 6 of the drawings, while it differs essentially from the above, is no less important, it being such that when the bolt or bar upon which the thread is to be formed is placed in the guide *G*, the axis of one of such shafts will be above the axis of such bolt, or rod, while the axis of the other or opposite shaft will be as much below said axial line of the bolt.

The necessity for the above-described arrangement will be apparent, when it is remembered that without it no longitudinal movement of the rod or bolt would be caused if the centres of these shafts were placed in the same horizontal plane, as in such an event the disks or cups would revolve without forming any screw-thread upon such bolt.

It is a well-known fact that the angles of the thread upon any bolt, supposing the bolt to be placed in a horizontal position, is in one direction upon its upper surface, while it is in the opposite direction upon its lower surface, which fact will still further explain the necessity of placing the shafts as above described, so that one of the disks, or the projections formed thereon, may act upon that portion of the rod or bolt which is above its centre, and the other upon the opposite angles, which are below such centre.

C C' represent gear-wheels, which are to be secured to the shafts *B B'*, for the purpose of communicating motion to the same.

D D' represent pinion-gears, which, in the present case, are secured to shafts which are mounted in bearings *c c'*, formed in the under side of the frame *A*, as shown in fig. 2. These pinions mesh with and rotate the wheels *C C'*, as clearly shown in the same figure.

E E' represent pulleys, which are to be secured to the outer ends of the shafts upon which the pinions *D D'* are secured.

On these pulleys pass the belts which are to drive the machine.

Fig. 6 shows how these machines may be arranged upon a table or frame, and be driven by belts passing down through such table, to any shaft below.

When each of the pulleys is driven from one driving-shaft, it will be necessary to cross one of the belts, as it is necessary that one of the disks or cups which form the thread should rotate in one direction, and the other in the opposite direction.

F F' represent the thread-forming disks or cups, which are to be secured to the shafts *B B'*.

These disks may be constructed in the form of plates, having a hole for securing them to the shafts, and an

overhanging or projecting flange upon their edges, for the reception of the concentric grooves which alternate with the concentric projections thereon, for the purpose of forming the screw, or they may be made in the form of semispheres, as shown in the drawings, and have the grooves and projections formed upon their outer edges, as shown in fig. 4.

These disks or cups being attached to the shafts B B', it follows that the effects above described, as resulting from the arrangements of such shafts, in connection with these disks, will be produced.

While the revolution of the disks, arranged as set forth, would cause a forward feed to the bar placed between them, this motion would be irregular; but when the projections from the faces have taken hold of the bar and compressed the thread, the concentric projections succeeding the first one, bearing against the sides of the thread, will serve to control the movement of the bolt, and cause it to be fed regularly forward, so as to form a thread of a uniform pitch.

G represents the guide for the rod or bolt upon which the screw is to be formed. It consists of a thin piece of metal, which may be of the form shown in the drawings, and have a slot through its centre, of the width of the diameter of the bolt to be threaded.

Upon each end of this flattened and slotted guide there is to be formed a tubular projection, it being fixed in place by boxes formed in or secured to frame A. Through these hollow journals the rod or bolt to be threaded passes, as shown in fig. 1 of the drawings.

The socket G' of the guide has cut on its inner face the thread of a female screw, of the same pitch as that to be cut on the rod or bolt.

This screw, when it receives the thread on the bolt, serves to control the movement of the latter, a function which becomes essential when, in cutting tapering-pointed bolts, (as shown in fig. 7,) the innermost of the concentric projections on the disks F cease to bear upon the thread which is being formed.

As the thread is raised, in part, above the original surface of the rod or bolt, the latter will pass through the guide, and the threads only will engage those of the female screw. This raised thread is not properly shown in fig. 7, which might mislead, unless this explanation were made.

In order that the outermost of the concentric projections may act upon the rod, the edge of the disk should be bevelled, as shown.

When it is desired to form the threads of a given length upon a number of bolts or rods, a gauge-rod may be inserted into one of the hollow journals of the guide G, as shown in fig. 4.

The rod or bolt to be threaded is to be passed through the opposite journal, and pushed forward until its inner end comes in contact with such gauge-rod, when the machine is to be put in motion, as a consequence of which, the bolt will be threaded from the point where the disks come in contact with it, to its end.

This gauge-rod may be set so as to allow a thread of any desired length to be formed, and be held in the desired position by means of a set-screw, as shown in fig. 4.

H represents a handle or lever, which is attached to screws, which are for a purpose soon to be described.

This handle or lever is to be formed with an aperture in each of its ends, to receive the ends of the screws K K', it being so formed as to extend from one end of the machine to the other, as shown in fig. 1, and it may be furnished with a guide, in which to move, and by which it may be held in any desired position, as shown in fig. 3.

K K' represent hollow screws, which pass through projections formed upon boxes b', in which the shafts B and B' rotate.

These screws bear against the ends of the shafts, as shown in fig. 6, and are for the purpose of being actuated by the handle or lever H, so as to force the thread-forming disks or cups nearer together, so that when they commence to act upon the bolt or rod, to form the thread thereon, only a slight indentation will be made, but so that they may be forced together gradually, until they shall penetrate the bolt a sufficient distance to form a perfect thread.

Through each of these screws a rod passes, which is to be secured to the shafts B B', and is to extend beyond the ends of screws K K', for a distance sufficient to receive a collar upon that portion which is outside of the handle or lever, so that when said handle is turned in a direction opposite to that which forces the disks together, it will cause the screws to be turned in an opposite direction, and thus draw the disks apart, preparatory to receiving another bolt to be threaded.

I, in fig. 6, shows various arrangements of belts, which may be adopted in driving these machines.

The operation of my improved screw-forming machine is as follows:

The parts having been constructed and arranged as shown in fig. 1, the lever or handle H being in the position shown in red lines in fig. 1, the bolt or rod is to be inserted into the guide G, and between the edges of the disks or cups F F', and the machine be put in motion through the above-described devices for that purpose, when the handle is to be turned to the position shown in fig. 1, or so far in that direction as may be found necessary to cause the disks to approach so near each other as to form the thread upon the bolt.

As a consequence of the above arrangement of the disks or cups which form the threads, they will, so soon as they come in contact with the bolt or rod to be threaded, cause the same to rotate within its guide, and a screw-thread corresponding to the form and pitch of the depressions and projections will be formed, into which the projections nearer the inner edge of the disks will enter, and thus cause the required longitudinal movement of the bolt or rod.

I am aware that machines have been constructed for various purposes, such as crushing quartz, grinding apples, grinding paints, and straightening round bars of iron, in which conical heads or plates have been used, the faces of said plates, where opposed, being, however, parallel with one another, and also that in such machines the shafts have been set at an angle to one another, and that some of them have their axes in different planes, and that several of them have also screws, for adjusting the distance between the plates.

I do not, therefore, claim any of these features broadly, as having been first used by myself, but limit my claims to such modifications of construction and arrangement as adapt this machine to the manufacture of screws upon rods or bolts.

Having thus described my invention,

What I claim, and desire to secure by Letters Patent, is—

1. The combination of a pair of circular disks, each with a lateral surface, upon which is formed an annular die, composed of a series of concentric screw-forming projections, lying in the same plane, arranged so that their contiguous and operative faces shall be somewhat inclined to one another, and at different elevations, on axes lying in different vertical and horizontal planes, substantially as set forth.

2. An improved screw-forming machine, constructed substantially as herein described, in which the spiral thread is formed upon a bar or rod, by the compression of two disks or cups, each having on its face concentric projections and grooves, the edges of said projections being, on each disk, on the same plane, and the faces of said disks being set at an angle to each other, and said disks revolving in opposite directions,

upon axes in different vertical and horizontal planes, equidistant above and below the axis of the rod or bar subjected to their action, substantially as set forth.

3. In combination with the screw-threading disks, F F, constructed and arranged to operate substantially as set forth, the guide G, having an internal thread at G', substantially as and for the purpose set forth.

4. The combination of the screw-threading disks, the tubular guide, and the adjustable rod placed in the latter, for regulating the length of the thread to be cut, substantially as set forth.

5. The arrangement of the screws K K', handle or lever H, and the rods which are secured to the ends of the shafts carrying the thread-forming disks, in virtue of which said disks are equally and simultaneously actuated, both in approaching toward and receding from each other, substantially as and for the purpose set forth.

TREAT T. PROSSER.
